UNITED STATES PATENT OFFICE.

ELMER M. JONES, OF ATLANTA, GEORGIA, ASSIGNOR TO JONES SIGNAL SYSTEM COMPANY, OF ATLANTA, GEORGIA, A CORPORATION OF GEORGIA.

AUTOMATIC TRAIN-STOP.

1,116,437.

Specification of Letters Patent.

Patented Nov. 10, 1914.

Application filed August 3, 1909. Serial No. 510,994.

To all whom it may concern:

Be it known that I, ELMER M. JONES, a citizen of the United States, residing at Atlanta, in the county of Fulton and State of Georgia, have invented a certain new and useful Improvement in Automatic Train-Stops, of which the following is a full, clear, and exact description, reference being had to the accompanying drawings.

10 This invention relates to mechanism whereby a train approaching a block which is occupied or which, for any reason, if out of commission, may have the brakes automatically applied thereto if the speed of the 15 train exceeds a certain predetermined limit and be kept on until the train is brought nearly to a standstill, at which time the brakes will be automatically released.

The objects of the invention are to provide a comparatively simple but efficient construction and arrangement of parts whereby the above result may be accomplished; also to provide a train with signal and brake operating devices adapted to 25 operate with track mechanism whereby a single mechanism may operate both operating devices or only one of said operating devices, according to conditions to be described hereinafter.

30 Generally speaking, the invention may be defined as consisting of the combinations of elements embodied in the claims hereto annexed and illustrated in the drawings forming part hereof, wherein Figure 1 represents a diagrammatic view, certain parts being shown in section, of a system embodying my invention; Fig. 2 a longitudinal sectional view through a casing, which may be carried by the locomotive, showing the 35 mechanism whereby the brakes may be automatically applied and released, and Fig. 3 a transverse sectional view through said casing.

40 Describing the parts by reference characters, 1 denotes a track; 2 the wheels of a locomotive, and 3 a centrifugal governor of any approved type, which may be conveniently driven from an axle of the locomotive. The governor comprises a pair of 45 balls 4, adapted to be thrown outwardly by centrifugal action through the rotation of the shaft 5, and 6 a sleeve mounted on said shaft and adapted to be raised and lowered by the movement of said balls. This sleeve

is provided with a pair of contact rings 7 and 8, the purpose and operation of which will be described hereinafter.

9 denotes a shaft, which may be conveniently mounted within a box or casing 10. The bottom of the casing is provided with 60 openings 11 and 12 for the accommodation of levers 13 and 14, which are sleeved upon said shaft. As will appear more particularly by reference to Fig. 3, the lower end of lever 14 projects below the lower end of 65 lever 13, whereby the former lever can be engaged and rocked by means of a track projection or ramp which will clear the lower end of lever 13, both of said levers being adapted to be rocked by means of a 70 track projection or ramp, such as 15, which projects upwardly a sufficient distance to be engaged by the lever 13. The lever 14 may be employed to operate a cab signal, such for instance as shown in my application 75 No. 456,423, filed October 6th, 1908. The purpose of lever 13 is, when engaged by such ramp or projection, to open a valve in the train pipe and thereby cause the brakes to be automatically applied in a well known 80 manner. The construction and arrangement of parts whereby this result may be accomplished will now be described.

16 denotes a section of the train pipe and 85 17 the stem of a valve therein. This valve stem is connected to a lever 18, which extends on both sides of said stem and is connected at its lower end to a link 19, by means of a pin 20 carried by said lever and a slot 21 in said link, said pin and slot providing a lost-motion connection between the lever and link. The pipe section 16 preferably extends into the casing 10, projecting through the lower end thereof. One end 90 of the link 19 is pivotally connected to a saddle 22, which is provided with arms 22^a sleeved upon the shaft 9 and carries a solenoid 23. The upper end of the lever 13 is curved, as shown at 24 and this curved portion of the lever is provided with a radial 95 shoulder, 25. A corresponding partly cylindrical recess 26 is formed in the lower and rear portion of the saddle, between the arms 22^a.

100 27 denotes a solenoid core, the same projecting downwardly into a suitable bore formed in the saddle 22 and having at its lower end a head 28 adapted, when the sole-

noid is deenergized, to be engaged by a pin 29 projecting through the front wall of the saddle. In this condition of the solenoid, the head 28 projects beyond and to the rear 5 of the curved surface 26 and in position to be engaged by shoulder 25 when the lower end of the lever 13 is moved to the right; that is to say, when the train is moving in the direction of the arrow shown in Fig. 1.

10 The saddle 22 is provided with a cam projection 30, which is shown in Figs. 2 and 3 as also sleeved upon the shaft 9 and is adapted to engage a lever 31, which is shown as pivoted at its rear end and extending in the path of movement of the cam 30 and normally supported thereby. The front end of lever 31 is connected to a link 32, the upper end of which is pivotally connected to a rod 33 having slots 34, 35 15 therein through which project pins 36 and 37 carried by the outer ends of levers 38 and 39, respectively. These levers are connected to the stems of valves 40 and 41, respectively, in pipe sections 42, 43, respectively. The stems of valves 40 and 41 are also provided with arms 44 and 45, respectively, which project through slots in the piston rod 46 projecting beyond the end of the cylinder 47. The end of the cylinder 20 opposite the arms 44 and 45 is connected by pipe section 48 with the casing 49. This casing, as will appear by reference to Fig. 1 is connected with a pipe section 50, the opposite end of which is connected with a cylinder 51.

25 52 denotes a solenoid which is located above the casing 49 and is provided with a core 53 the lower end of which projects into and is guided by said casing. This core is 30 provided with a guiding projection 53a and with a valve projection 54 adapted, when the solenoid is deenergized, to close the port in the casing which communicates with pipe section 50.

35 55 denotes a reservoir which is connected with the train-pipe section 56, a check valve 57 being provided in said section adjacent to the reservoir and adapted to be seated by the pressure of air within the reservoir. A 40 pipe section 58 extends from the reservoir to the casing of the valve 40. The pipe sections 42 and 43 communicate with a pipe section 59 which is connected with the front end of the cylinder 51.

45 55 and 61 denote short pipe sections extending from the valves 40 and 41, respectively, and communicating with a pipe section 62 which is connected to the rear end of the cylinder 51. A discharge connection 50 63 extends from the valve 41, intermediate between sections 43 and 60. The cylinder 51 is provided with a piston 64, the rod 65 whereof projects through the rear end of the cylinder and is connected to the upper end

of the lever 18, such connection being conveniently made by providing the upper end of the lever with forks 18a having each a slot 18b therein, with pins 66 extending from the piston rod through said slots.

67 denotes a spring which tends to force 70 the piston and the upper end of lever 18 forwardly, or to the left. This spring may be conveniently applied to the piston rod between the piston head and the rear end of the cylinder, as shown in Fig. 2. A suitable 75 stop 68, provided within the cylinder, limits the movement of the piston head to the right or rear end of the cylinder. In Fig. 1 the spring 67 is shown diagrammatically as applied to the lever 18 in such manner as to 80 tend to force the upper end of the lever and the piston rod to the left or front.

The solenoid 52 receives its current from a suitable source of electrical energy, shown at 85 69. The circuit including the solenoid is normally broken by the separation of the terminal 70 from the circuit-closing ring 8. The solenoid 23 receives its current from a source of electrical energy 71, but the circuit including such solenoid is normally broken 90 by the separation of the terminal 72 from the circuit closing ring 7. Both of these segments are carried by the sleeve 6.

In operation, suppose the train to be approaching a block which is occupied by another train or, for any other reason, is out of commission. Under such conditions, the ramp or projection 15 will be in position to be engaged by the lever 13. Under normal conditions, the air in reservoir 55 flows 100 through pipe sections 58 and 42 into the front or left-hand end of cylinder 51, thereby keeping the piston 64 in the position shown in the drawings and the valve in pipe 16 shut. Valve 41 in this condition closes 105 pipe section 43. The end of the cylinder on the opposite side of piston 64 is vented through pipe sections 62, 60 and 63. The lower end of lever 13 strikes the ramp or projection 15 and is rocked to the right 110 against the action of the springs 73, 74. As lower end of this lever is rocked to the right, the shoulder 25 engages the side of the head 28, thereby rocking the saddle 22 and solenoid 23 to the left. The cam 30 lifts the link 115 32 and, as the pins 36 and 37 near the lower ends of the slots 34 and 35, respectively, this lifting action reverses the position of the valves 40 and 41, cutting off the supply from reservoir 55, pipe 42 and the 120 left hand end of the cylinder and permitting air from said reservoir to pass through valve 40 and pipe sections 61 and 62 to the right hand end of said cylinder. At the same time valve 41 closes communication 125 between the cylinder and pipe 63 and establishes communication between the left-hand end of cylinder 51 and the vent-pipe sec-

tion 63 through pipe sections 59, 43 and the open valve 41. The piston 64 moves to the left under the pressure of the air and the action of the spring 67, thereby opening the valve 5 in the pipe section 16 and applying the brakes. The length of the slot 21 will be such that this preliminary rocking of the saddle 22 will be permitted. Furthermore, owing to the manner of connecting the rod 10 33 with the arms 38 and 39, an appreciable interval of time will elapse between the rocking of the saddle and the rocking of the lever 18 by the piston rod 65 to permit of the full operation of the cam to open the 15 valves 40 and 41 before the lever 18 will be shifted. When this occurs, the pin 20 striking the right-hand or rear end of the slot 21 will restore the saddle and solenoid to the position shown in the drawings. By 20 the construction shown in Fig. 2, after the valves 40 and 41 have been reversed, the connecting rod 32 is free to drop to the position shown without operating the valves, owing to the lost-motion connection there- 25 between. But for this lost-motion connection, the weight of the parts might be sufficient to cause the reversal of the valves 40 and 41.

As a necessary condition to the operation 30 above described, the solenoid must be de-energized. This will occur at any time when the speed of the train is above the predetermined safety limit. Suppose, for instance, that five miles per hour is such predetermined limit. The governor parts will be so arranged that, when the speed falls to five miles per hour, the terminal 72 engages the circuit-closer 7, closing the circuit including the solenoid 23 and removing the head 28 40 from the path of movement of the upper end of lever 13. Under these conditions, the lever 13 will be rocked by its ramp or projection without applying the brakes.

Reference has been made to the automatic 45 release of the brakes when the train is nearly at rest. The air which has been admitted to the right or rear hand end of the cylinder 51 is retained therein by the valve 41 and the projection 54 which closes the port in the 50 casing 49. When the train is nearly at a stand still, the dropping of the sleeve 6 will bring the terminal 70 into contact with the circuit closer 8 and will close the circuit including the solenoid 52. The core 53 is then 55 drawn upwardly and air from reservoir 55 and cylinder 51 can pass through pipe sections 50 and 48 into the cylinder 47, thereby operating the piston in said cylinder and the piston rod 46, to cause the reversal of valves 60 40 and 41. To permit of the original movement of the valves by link 32 and rod 33, the piston rod 46 is provided with slots 44^a and 45^a which will permit of the consequent rocking of arms 44 and 45 by the movement

of the link 32. The operation of the piston 65 and cylinder 47 rocks the valves 40 and 41, such rocking being permitted by the pin-and-slot engagement between arms 38 and 39 and the rod 33. Thereupon the valves are set to the position shown in Fig. 1, shutting off communication between the reservoir 55 at the right hand end of the cylinder 51, venting the right hand end of the cylinder through the outlet connection 63 and supplying the left hand end of cylinder 75 through valve 40 and pipe sections 42 and 59. This operation causes the piston 64 to be restored to its original position and to close the valve in train pipe section 16, thus avoiding any waste of air. 80

The connection between the lever 13 and saddle 22 is such as to enable the train to be backed and the lever 13 to be moved by engagement with a ramp or projection, in a direction contrary to the arrow shown in Fig. 1 without operating the saddle and without affecting the valve in train pipe 16. The springs 73 and 74 will restore the lever to the initial position shown in Fig. 1 after the lever has passed over the ramp. In Fig. 2 a single spring 74 is shown as applied to a plunger 74^a which resists the movement of the lever 13 in either direction and restores said lever to normal position after a ramp has been passed. 95

The diagrammatic illustration of my invention, which is shown in Fig. 1, differs in some structural details from the embodiment shown in Figs. 2 and 3. For instance, the connection between the piston rod 46 and the valves 40 and 41 is shown in the diagram as made through a bell-crank lever 75, one arm of which is connected to the piston rod and the other arm to the link 32 by means of a pin-and-slot connection, enabling the link 32 to be lifted by the cam 30 and enabling the piston rod, when air is supplied to the cylinder 47 through the casing 49, to operate the link 32 and shift the valves. Furthermore, the spring 67 is shown as connected to the lever 18, but it serves the same purpose as the like-numbered spring in Fig. 2, as it tends to move the lever and the piston rod 65 forwardly or to the left. Furthermore, instead of using a separate rod 33 having a slotted connection with arms projecting from the valves, the link 32 is shown as connected directly to the valves and has a slotted connection with the piston rod 46, through bell-crank lever 75. The principle of the invention disclosed in Figs. 2 and 3 is, however, embodied in the diagrammatic representation of Fig. 1, and the mode of operation is substantially the same in both instances. 115 120 125

It will be understood that the lever 14 will be operated by a ramp or projection which is distant from the block approached and

which does not project a sufficient distance to operate the lever 13 and that the latter lever will be operated by a ramp or projection 15 which is adjacent the block approached and which projects a sufficient distance to operate both levers.

Having thus described my invention, what I claim is:

1. In an automatic train stop, the combination of a train pipe, a valve therein, and means for operating said valve, said means comprising a cylinder, a piston in said cylinder, a piston rod, a connection between said rod and said valve, fluid pressure pipes connected with said cylinder at opposite ends thereof, a valve mechanism controlling the supply of fluid to opposite ends of said cylinder, and a second cylinder having a piston therein connected to said valve mechanism, said last named piston being controlled by the speed of the train for automatically operating said mechanism to supply fluid to either end of the cylinder.
2. In an automatic train stop, the combination of brake applying means, means for operating the former means, the latter means comprising a cylinder, a piston in said cylinder, a piston rod, a connection between said rod and the brake applying means, fluid pressure pipes connected with said cylinder at opposite ends thereof, valve mechanism controlling the supply of fluid to opposite ends of said cylinder, and a second cylinder having a piston therein connected to said valve mechanism, said last mentioned piston being controlled by the speed of the train for automatically operating said mechanism to supply fluid to either end of the cylinder.
3. In an automatic train stop, the combination of a cylinder, a source of fluid pressure supply adapted to communicate with opposite ends thereof, valve mechanism arranged to open the supply to one end of the cylinder and vent the other end, brake-applying means, a piston in said cylinder, a connection between said piston and said means, and a second cylinder having a piston therein connected to said valve mechanism, said last named piston being controlled by the speed of the train for automatically reversing the valve mechanism.
4. In an automatic train stop, the combination of brake-applying means, a cylinder, a piston therein, a piston rod connected with said brake-applying means, pipes arranged to supply pressure fluid to opposite ends of said cylinder, valves in said pipes adapted to permit the supply of pressure fluid to either end of the cylinder while venting the other end, a second cylinder having a piston therein connected to the

valve mechanism, said last mentioned piston being controlled by the speed of the train for operating them to permit the flow of pressure fluid to one end of the cylinder when the speed of the train exceeds a predetermined limit, and means for reversing said valves when the speed of the train falls below a predetermined limit.

5. In an automatic train stop, the combination of brake-applying means, means for operating the former means, the latter means comprising a cylinder, a piston therein, a piston rod, a connection between said rod and the brake-applying means, valve mechanism adapted to permit the supply of fluid to either end of the cylinder while venting the other, a second cylinder having a piston therein, said piston being controlled by the speed of the train, said piston having connections with said valve mechanism for operating said valve mechanism in one direction when the speed of the train exceeds a predetermined limit, and electrically controlled means for reversing said valves when the speed of the train falls below a predetermined limit.

6. In an automatic train stop, the combination of a train pipe, a valve therein, a cylinder, a piston therein, a piston rod, means connecting said piston rod and said valves, a source of fluid pressure supply, pipes connecting the same with opposite ends of the cylinder, valve mechanism arranged to permit the flow of fluid to one end of the cylinder when the speed of the train exceeds a predetermined limit and to the other end of the cylinder when the speed of the train falls below a predetermined limit, a second cylinder, a piston therein, operative connections between said piston and said valves, a conduit connecting the latter cylinder with one end of the former cylinder, a valve in said conduit, mechanism for operating said valve, and a governor arranged to control the said mechanism when the speed of the train falls below said predetermined limit, thus reversing the valve mechanism to cause the pressure fluid to flow to the opposite end of the cylinder.

7. In an automatic train stop, the combination of brake-applying means, a cylinder, a piston therein, a piston rod, means connecting said piston rod and said means, a source of fluid pressure supply, pipes connecting the same with opposite ends of the cylinder, valve mechanism arranged to permit the flow of fluid to one end of the cylinder when the speed of the train exceeds a predetermined limit, and means for automatically reversing said valve mechanism to permit the flow of fluid to the opposite end of the cylinder when the speed of the train falls below a predetermined

limit, the latter means comprising a cylinder, a piston therein, and lost-motion connections between said piston and said valve mechanism, a conduit connecting the latter 5 cylinder with one end of the former cylinder, a valve in said conduit, and an electromagnet for operating said valve and arranged to have its circuit closed when the

speed of the train falls below said predetermined limit.

In testimony whereof, I hereunto affix my signature in the presence of two witnesses.
